[57] CLAIM

The ornamental design for a scroll saw, as shown and described.

DESCRIPTION

FIG. 1 is a left side elevational view of the scroll saw, showing my new design;

FIG. 2 is a front elevational view thereof;

FIG. 3 is a right side elevational view thereof;

FIG. 4 is a rear elevational view thereof; and

FIG. 5 is a top plan view thereof.

The bottom of the scroll saw is flat and unornamented.
